D10-1.

OR D 7,769 EX

Clock

UNITED STATES PATENT OFFICE.

FLORENCE KROEBER, OF HOBOKEN, NEW JERSEY.

DESIGN FOR CLOCK-CASES.

Specification forming part of Design No. 7,769, dated September 22, 1874; application filed August 15, 1874.
[Term of Patent 3½ years.]

CASE D.

To all whom it may concern:

Be it known that I, FLORENCE KROEBER, of Hoboken, in the county of Hudson and State of New Jersey, have invented a new and original Design for a Clock, of which the following is a specification:

The accompanying engraving represents a face view of my new design for a clock.

This invention relates to the new ornamentation of the case of a pendulum-clock.

The base *a* of the clock is of suitable design, but somewhat wider than the case proper. Rosettes *b b*, carrying leaves *c c*, join

the base to the straight sides of the clock-case. The top of the clock-case projects at *d d* slightly beyond the straight sides of the case, and is decorated by two floral scrolls, *e e*, which appear to brace the crown ornament *f f*, as shown.

I claim as my invention—

The design for the ornamentation of a clock, as shown.

F. KROEBER.
